UNITED STATES PATENT OFFICE.

MARSHALL J. HUGHES, OF NEW YORK, N. Y.

IMPROVEMENT IN STEREOTYPE-PLATES.

Specification forming part of Letters Patent No. **146,454**, dated January 13, 1874; application filed December 8, 1873.

To all whom it may concern:

Be it known that I, MARSHALL J. HUGHES, of the city, county, and State of New York, have invented a new and Improved Reversible Stereotype-Plate; and I do hereby declare that the following is a full, clear, and exact description of the same, reference being had to the accompanying drawing forming a part of this specification, in which—

Figure 1 is a perspective view of the double-faced stereotype-plate cast upon a flexible sheet-metal plate, part being cut away to show perforations in the latter. Fig. 2 shows a modification.

My invention consists, first, in a double-faced or reversible stereotype-plate. It consists, secondly, in providing a plate with a lining or lateral extension of sheet metal to facilitate locking up the same.

Referring to the drawing, the plate A has a type-face on each side, thus resembling two plates placed back to back and firmly joined together. In producing the plate, I place the faces of two matrices opposite and closely approximated in the mold or casting-box, and confine them by a gage of suitable construction, and (by other means and modes of procedure not needful to describe here) the metal being poured in the plate is cast, and only requires to be trimmed in the usual way to be ready for use. It is obvious that such a plate includes in the same space double the amount of reading-matter of the ordinary plate, since the matter on one side or face is of a different character from that on the other. I usually cast it of the same, or nearly the same, thickness and weight as those of the ordinary kind; but its thickness may range from one-sixteenth of an inch to an inch, or what is termed "type high."

To provide the plate with the lining or extension before referred to, I employ sheet tin, copper, zinc, or other analogous material. The same is placed in the casting-box in suitable local relation to the matrices, and the metal cast upon and around it, leaving lateral margins C. The piece of sheet metal may be imperforate, or perforated, as shown in Fig. 1, to allow the melted metal to flow through and join the two faces of the plate more firmly together. In either case the lining may be of the same rectangular form as the plate; or strips D may be employed instead, the same extending inward only a short distance from the lateral edges of the plate.

In locking up the plate when cast with the lining or margin, the latter is first bent down at right angles, and the plate then placed on the block or furniture to raise its face type high. The lining will then be firmly secured by the pressure of the column-rules or other devices in the chase used. When the plate is cast type high, the extension may be, of course, dispensed with. When the required number of impressions have been taken from one face of the plate it is reversed on the block and secured as before.

Having thus described my invention, what I claim as new is—

1. A double-faced or reversible stereotype-plate, substantially as shown and described.
2. The combination, with a stereotype-plate, of an extension or margin of flexible material, as shown and described.
3. The combination of a perforated flexible plate with the reversible plate, as specified.

MARSHALL J. HUGHES.
